[57] CLAIM

The ornamental design for a chair, as shown.

DESCRIPTION

FIG. 1 is a front perspective of a chair showing my new design;
FIG. 2 is a top plan view;
FIG. 3 is a bottom plan view;
FIG. 4 is a front elevational view;
FIG. 5 is a rear elevational view;
FIG. 6 is a left side elevational view;
FIG. 7 is a right side elevational view;
FIG. 8 is a front perspective view of a chair showing a second embodiment of my new design;
FIG. 9 is a top plan view of FIG. 8;
FIG. 10 is a bottom plan view of FIG. 8;
FIG. 11 is a front elevational view of FIG. 8;
FIG. 12 is a rear elevational view of FIG. 8;
FIG. 13 is a left side elevational view of FIG. 8;
FIG. 14 is a right side elevational view of FIG. 8;
FIG. 15 is a front perspective view of a chair showing a third embodiment of my new design;
FIG. 16 is a top plan view of FIG. 15;
FIG. 17 is a bottom plan view of FIG. 15;
FIG. 18 is a front elevational view of FIG. 15;
FIG. 19 is a rear elevational view of FIG. 15;
FIG. 20 is a left side elevational view of FIG. 15;
FIG. 21 is a right side elevational view of FIG. 15;
FIG. 22 is a front perspective view of a chair showing a fourth embodiment of my new design;
FIG. 23 is a top plan view of FIG. 22;
FIG. 24 is a bottom plan view of FIG. 22;
FIG. 25 is a front elevational view of FIG. 22;
FIG. 26 is a rear elevational view of FIG. 22;
FIG. 27 is a left side elevational view of FIG. 22;
FIG. 28 is a right side elevational view of FIG. 22;
FIG. 29 is a front perspective view of a chair showing a fifth embodiment of my new design;
FIG. 30 is a top plan view of FIG. 29;
FIG. 31 is a bottom plan view of FIG. 29;
FIG. 32 is a front elevational view of FIG. 29;
FIG. 33 is a rear elevational view of FIG. 29;
FIG. 34 is a left side elevational view of FIG. 29; and,
FIG. 35 is a right side elevational view of FIG. 29.
